M WILDER.
THRESHING MACHINE.

No. 60,813

Patented Jan. 1, 1867.

United States Patent Office.

MARK WILDER, OF EAST PRINCETON, MASSACHUSETTS.

Letters Patent No. 60,813, dated January 1, 1867.

IMPROVEMENT IN THRESHING MACHINES.

The Schedule referred to in these Letters Patent and making part of the same.

TO ALL WHOM IT MAY CONCERN:

Be it known that I, MARK WILDER, of East Princeton, in the county of Worcester, and Commonwealth of Massachusetts, have invented certain new and useful improvements in Threshing Machines and Dust Removers; and I do hereby declare that the following is a full, clear, and exact description of the same, reference being had to the accompanying drawings, forming a part of this specification, in which—

Figure 1 represents a perspective view of my said improved machine.

Figure 2 represents a longitudinal central section; and

Figure 3 represents a cross-section on line A B, fig. 2, looking in the direction of arrow 5, fig 1.

The object of my invention is to relieve the men who work about the machine from the inconvenience and injury resulting from working in the dust occasioned by the threshing operation; also, to obtain a more perfect separation of both grain and dust from the straw and from each other.

In the drawings, A A A A represent a strong frame, in which are supported, in proper bearings or boxes, the shafts of the threshing cylinder B and fans C and D. The sides and top of the machine are closed, as nearly air and dust-tight as practicable, while the front is closed, except at the place where the unthreshed grain is fed in. The rear of the machine is also closed in the same manner, except at the places where the straw and dust are discharged, as will be hereafter explained. The sides of the machine are provided with doors, as indicated in fig. 1, which can be opened to examine the operation or repair the machine whenever desired. Fan C works in a case, C¹, which opens at each end into the box E, and is open at the bottom, as shown at a. Fan D also works in a case, F, arranged within the closed sides of the machine. Case F is open at each end, and consequently the air and dust within the closed sides of the machine will be drawn in and forced out of the case F whenever the machine is in operation, the air and dust passing out of the spout or vent-way G. H is the stationary threshing-bed, and for the convenience of repairs, or for cleaning of either the bed or cylinder B, the bed is fastened to and supported at each end by pieces I, one of which is shown in fig. 2. Pieces I are hinged at their lower ends, as indicated at b, so that when the hinged standards J are turned forward, the bed H can be lowered. K is the separating board or frame, having holes, c, for the grain to pass through, and long notched strips, L, to support the straw and work it along to the rear of the machine. The separating frame K is supported in an inclined position by hinged arms, M, two upon each side. When the machine is in operation, frame K is moved back and forth by means of arm N, which is fastened to frame K, and is also connected to crank d, on the end of shaft e, which is operated by belt f, which runs upon pulley g. O is a lattice frame, which is suspended at front by straps, h, one of which is seen in the drawings. This frame, O, is supported in the rear by cords or chains, i, which are attached to a shaft, k, by means of which the rear of frame O can be raised or lowered whenever desired. The operation of the machine is as follows: Motion being imparted to the threshing cylinder B and fans C and D in any proper manner, the grain to be threshed is placed upon table P, from which it is fed to cylinder B in the ordinary manner. As fan C turns in the same direction as cylinder B, the straw is prevented from being carried back over cylinder B by the strong current of air which is forced by fan C through the opening a in case C' against the teeth m, and consequently my machine is not liable to clog up. Again, as the air to supply the fan C is drawn from box E, which is open only at the lower front corner, nearly all the dust, which would otherwise escape into the air in front of the cylinder, is drawn into box E, through the opening n, which is covered by guard-wires, o, attached to frame p, to prevent the straw from table P being drawn into box E and fan C. Frame p rests in the bent supports, q, from which it can be removed at pleasure. The straw is thrown back, by the combined action of cylinder B and fan C, in a very loose condition, against the lattice frame O, before it falls upon the separating frame K, and which operation conduces very much to the perfect separation of the grain from the straw and dust. As the straw is worked back by the action of the frame K, to be discharged therefrom at the rear, fan D draws a strong current of air through the same, which cleans it from dust. The action of fan D is such, too, as to cause a current of air to pass up through the holes in frame K, whereby the grain is allowed to fall upon the gathering boards, Q, free from floating dust. It will thus be seen, that by the action of fans C and D a partial vacuum is created within the case of the machine, whereby currents of air are passing in through every hole and crevice, thus preventing the escape of dust from the machine except through the spout or vent G, which may be extended sufficiently far from the machine to

discharge the dust or dirt out of the way of the workmen engaged in operating the machine. Frame O, while it arrests the straw, and prevents it from being thrown or drawn up around the ends of the fan-case F, readily yields sufficiently to prevent the straw from clogging up in the machine. In some machines the threshing cylinder turns in an opposite direction from that above described and shown in the drawings. In such cases the fan C would have to be placed below the cylinder, unless wind chests were used to convey the air to the proper position to act as described. Fan D may also be differently arranged, and still accomplish the same results; for instance, it might be placed on top of the machine, provided the arrangement was such that the fan would exhaust the air from the machine, and thus draw off the dust and dirt. The top, front, and ends of box E are so made that they can be quickly removed, together with fan C and the parts connected therewith, for the purpose of repairing the machine. The action of fan C, by forcing a strong current of air against the teeth m, and surface of the threshing cylinder B, forces the flying dust back into the machine, and prevents its escape into the air in front of the machine. R is an adjustable damper, by means of which the opening at the rear of the machine can be enlarged or contracted, to regulate the current of air drawn in by fan D.

Having described my improved threshing machine and dust remover, what I claim therein as new, and of my invention, and desire to secure by Letters Patent, is—

1. The combination of fan D with the separating parts of the machine, substantially as and for the purposes stated.
2. The combination of fan C with the threshing parts of the machine, substantially as and for the purposes stated.
3. The combination and arrangement of fans C and D with cylinder B, substantially as set forth.
4. The combination and arrangement of fans C and D, and threshing cylinder B, with frames O and K, as and for the purposes set forth.
5. The combination with the front of box E of the guards o and adjustable frame p, substantially as and for the purposes set forth.
6. Supporting bed-piece, H, by means of hinged supports I and J, for the purposes stated.
7. The combination of the adjustable damper R with the fan D, substantially as and for the purposes set forth.

MARK WILDER.
